UNITED STATES PATENT OFFICE.

ROBERT WOOD, OF SYRACUSE, NEW YORK.

DESIGN FOR A DEFLECTOR.

SPECIFICATION forming part of Design No. 22,630, dated July 18, 1893.

Application filed April 15, 1893. Serial No. 470,538. Term of patent 14 years.

To all whom it may concern:

Be it known that I, ROBERT WOOD, of Syracuse, in the county of Onondaga, in the State of New York, have invented a new and useful 5 Design for Deflectors, of which the following, taken in connection with the accompanying drawings, is a full, clear, and exact description.

Figure 1, is a bottom view of the deflector. 10 Fig. 2, is a side or edge view thereof: these two views being deemed necessary to fully illustrate my design.

The leading feature of my design consists 15 in its being saucer-shaped, and the radially key-hole slots extending from a circle about the center.

a, is the center and base; and *b*— is the

rim concaved to give it a saucer-like appearance; and *c*— are key-hole slots emanating radially from the base. The regular curved 20 lines of the slots combined with the curved lateral surface of the deflector, present to the eye a very pleasing effect.

What I claim, and desire to secure by Letters Patent, is—

The design for a deflector substantially as 25 herein described and shown.

In witness whereof I have hereunto set my hand this 4th day of April, 1893.

ROBT. WOOD.

In presence of—

C. B. KINNE,

HOWARD P. DENISON.
